UNITED STATES PATENT OFFICE

120,410

DESIGN FOR A MATERNITY DRESS

Jack North, Cincinnati, Ohio

Application June 21, 1939, Serial No. 85,592

Term of patent 7 years

To all whom it may concern:

Be it known that I, Jack North, a citizen of the United States and a resident of the city of Cincinnati, in the county of Hamilton and State of Ohio, have invented a new, original, and ornamental Design for a Maternity Dress, of which the following is a specification, reference being had to the accompanying drawing, forming a part thereof.

Fig. 1 is a front view of my dress showing the side portions of the dress tied at the front.

Fig. 2 is a back view of my dress shown in Fig. 1.

Fig. 3 is a front view of the dress shown in Fig. 1 showing the skirt in extended position.

I claim:

The ornamental design for a maternity dress, substantially as shown and described.

JACK NORTH.
